United States Patent Office

Des. 178,472
Patented Aug. 7, 1956

178,472

AUTOMOBILE

Clifford C. Voss, Clawson, Mich., assignor to Chrysler Corporation, Highland Park, Mich., a corporation of Delaware

Application May 11, 1955, Serial No. 35,933

Term of patent 7 years

(Cl. D14—3)

Fig. 1.

Fig. 2.

Fig. 3.

Fig. 1 is a perspective view of an automobile showing my new design with the side opposite being similar to the one illustrated;

Fig. 2 is a front elevational view thereof; and

Fig. 3 is a rear elevational view thereof.

The characteristic features of my design reside in the portions shown by means of full lines in the drawing.

I claim:

The ornamental design for an automobile, substantially as shown and described.
